US00D581936S

(12) **United States Design Patent**
Hidaka et al.

(10) **Patent No.:** US D581,936 S
(45) **Date of Patent:** ** Dec. 2, 2008

(54) **FACSIMILE**

(75) Inventors: **Masataka Hidaka**, Kadoma (JP);
Junichi Ogawa, Kadoma (JP)

(73) Assignee: **Panasonic Corporation**, Osaka (JP)

(**) Term: **14 Years**

(21) Appl. No.: **29/304,213**

(22) Filed: **Feb. 27, 2008**

(51) **LOC (8) Cl.** 16-03

(52) **U.S. Cl.** **D14/469**

(58) **Field of Classification Search** D14/463-470;
D18/36-41; 358/400-404

See application file for complete search history.

(57) **CLAIM**

We claim the ornamental design for a facsimile, as shown and described.

DESCRIPTION

FIG. 1 is a top perspective view of a facsimile of the present invention;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken line showing of facsimile is included for the purpose of illustrating environment and forms no part of the claimed design.
